UNITED STATES PATENT OFFICE

LLOYD VAN SCIVER, OF CHESTNUT HILL, PENNSYLVANIA

WALKING STICK

Application filed February 3, 1932. Serial No. 590,701.

My invention relates to a pickup device having preferably the form of a cane, the device being intended for any use to which it may be adapted and is believed to be particularly well suited for convenient use by prospective mothers, invalids and others not able to easily stoop for the purpose of picking up different miscellaneous objects.

10 A purpose of the invention is to provide a novel device of the character indicated adapted to easy and inexpensive manufacture and well suited to the needs of service.

15 A further purpose is to combine a novel and effective pickup device with a hollow cane.

20 A further purpose is to provide a device that will appear to be and function as an ordinary cane and that will function as a pickup device at the cane end.

25 A further purpose is to use the lower end of a cane and the lower end of a finger having a swinging connection with the cane at an intermediate part thereof as cooperating pickup members.

30 A further purpose is to operate the opening and closing of a pickup device of the character indicated at the handle of the cane portion thereof.

35 Further purposes will appear in the specification and in the claims.

I have elected to show two only of the different forms of my invention, showing however also a detail modification and have selected forms and a detail modification that are practical and efficient in operation and which well illustrate the principles involved.

Figure 1 is a longitudinal sectional elevation of one embodiment of the invention.

40 Figure 2 is a view corresponding to Figure 1 but with the parts in a different position, Figure 1 showing the device in its normal or closed position and Figure 2 showing it open ready for pickup.

45 Figure 3 is a fragment of Figure 2 but showing the parts partially closed from the position of Figure 2 and in the act of pickup.

Figure 4 is an enlarged section taken upon the line 4—4 of Figure 1.

50 Figure 5 is an enlarged fragment of Figure 1.

Figure 6 is a section of Figure 5 taken upon the line 6—6 thereof.

Figure 7 is an enlarged section of Figure 1 taken upon the line 7—7 thereof.

Figure 8 is a perspective view of a detail.

Figure 9 is a longitudinal elevation, in part section, of a different form, shown in normal closed position.

Figure 10 is a view corresponding to Figure 9 except that the device shown closed in Figure 9, is open in Figure 10 and some portions not sectioned in Figure 9 are sectioned in Figure 10.

Figure 11 is a section taken upon the line 11—11 of Figure 9.

Figures 12 and 13 are fragmentary views showing in open and closed positions the cooperating pickup end portions of the cane and pickup device in forms thereof that are different from the corresponding pieces of Figures 9 and 10.

Figure 14 is a bottom plan view of Figure 13.

Like numerals refer to like parts in all figures.

Describing in illustration and not in limitation and referring to the drawings:

Describing the structure shown in Figures 1 to 8 inclusive, the combined cane and pickup device includes a hollow body 15, a pickup finger 16 and mechanism operative at the handle 17 of the cane for opening and closing the pickup finger with respect to the body.

The hollow body 15 may be exactly similar to the corresponding portion of a usual hollow cane and the pickup finger 16 may suitably, when closed, have an appearance of being an integral portion of the body 15, the device when closed desirably having the appearance of an ordinary cane.

The pickup finger 16 pivots at its upper end at 18 to the body and carries rigidly fastened to it at its pivot an arcuate pinion 19 that meshes with the teeth of a corresponding pinion 20, the pinion 20 being pivotally supported at 21 by the body and in turn meshing with the rack teeth 22 on the lower end of an operating link 23, the angular opening and closing of the finger with

respect to the body being thus determined by the vertical position of the link 23.

The upper end of the link 23 pivotally connects at 24 to one end of a rocker 25, the 5 rocker 25 being pivoted to the body at 26 and extending along the interior of the handle portion 17 of the cane.

The lever 25 that operates the link 23 and thereby the opening and closing of the pickup 10 finger is in Figure 1 a first class lever, spring pressed at 27 to open the pickup finger and adapted to be latched in closed position against the opening action of the spring.

The spring 27 is compressed between the 15 interior of the handle 17 and the rocker 25, being guided by a pin 28, the pin 28 extending downwardly across the interior of the handle through a perforation of the lever and the spring surrounding the pin.

20 Downward deflection of the right-hand end of the lever (Figures 1 and 2) raises the link 23 to move the pinions 19 and 20 in a direction to open the finger, for example to the position shown in Figure 2.

25 This opening will take place automatically if the spring 27 is free to act.

Normally the lever 25 is latched in the retracted position of Figure 1, thereby positioning the finger close against the device 30 and the lever 25 horizontal.

The latch mechanism as shown in Figures 1 and 2, includes a bolt 29 in the bored end of the lever 25, the bolt being spring pressed outwardly at 30 and with an outer end adapted to slide into a beveled recess 31 of an end portion of the handle.

35 The bolt 29 is provided with a downwardly projecting pin 32 operating in a suitable slot 33 of the lever.

40 The pin 32 suitably extends downwardly just far enough for easy operation by a finger of the user when the latch is in the closed position, that of Figure 1.

When a user loosens the latch the spring 45 27 automatically depresses the right hand portion of the lever to open the finger, as illustrated in Figures 2 and 3.

I preferably provide either one or both of the pickup members, either the swinging 50 finger or the lower portion of the device with a wedge surface 34 that functions much as an artificial finger nail to be inserted under any object to be picked up by the device from a floor.

55 I also preferably provide one of the cooperating jaw members, either the finger or the lower end of the body of the cane, with a magnet 35.

In the form described, the magnet 35 is 60 shown in the device, while the claw or artificial nail 34 is mounted upon the lower end of the finger.

As illustrated, the magnet 35 has been 65 made in the form of a rectangular piece of steel which in closed position of the finger is

received in a recess 36 of the claw member 34 of the finger. In Figure 2 the device is illustrated as positioned to pick up a spool 37, the finger 16 not yet having closed on to the spool. A user presses the lever 25 upwardly at the pin 32 which closes the finger to pick up the spool or other object as illustrated in Figure 3.

The details of the structure may be considerably varied to best suit the views of the individual user or manufacturer.

In the embodiment of Figures 9 to 12 the finger 16' is mounted upon the side of the cane toward the handle 17' instead of upon the opposite side thereof, as in the form first 80 described.

Also in the latter form the arcuate teeth 19' upon the upper end of the swinging finger 16' mesh directly with the rack teeth 22' instead of connecting to the rack through an intermediate pinion member 20 as in Figure 5.

The lever 25' operating in the handle 17' of the cane is as a result a third class instead of a first class lever, the lever being pivoted upon a pin 26' near the end of the handle.

The lever 25' is shown as comprising a flat strip of metal bent into a return hook at one end at 38 to ride upon the stationary pivot pin 26' and to permit longitudinal movement of the lever and at the other end is bent upwardly for a short distance at 39 to receive the downwardly directed hook end 40 of the link 23'.

A latch and finger engagement member 41 which may suitably be of metal, wood or composition is suitably fastened to the under side of the lever 25' and adapted to hold the lever in raised position by latching over an edge 42 of a perforation 43 in the bottom wall of the hollow handle 17'.

In the form of Figures 1 and 2 the finger is resiliently retracted and pressed toward its open position by means of the spring 27 in the handle of the cane.

In the form of Figures 9 and 10 however this function is performed by a flat spring 27' operating at the joint between the finger and cane body, one end of the spring being fastened at 44 to the body of the cane while the other is compressed against the finger.

In Figures 9 and 10 the swinging finger 16' is rigidly fastened to the pinion member 19' and is pivoted at 18' to a U-sleeve 45 that is fastened at 46 rigidly to the body of the cane above the pivot.

In the form first described, the wedge portion 34 of the pickup device was shown as an extension from the finger 16. In the form of Figures 9 and 10 however it is shown as an extension 34' from the body of the cane. In both forms at least one of the cooperating pickup members comprising the lower ends of the cane body and cane finger should desirably have a wedge projection 34 or 34' adapted to function as an artificial finger nail 130

while the other member is recessed at 47 to permit the nail member to close into an open space for tight closure of the finger.

Optionally the artificial nail may comprise 5 a portion of the magnet 35 or 35', this being indicated to be the case in Figures 9 and 10.

It will be understood that my device is to function both as a cane and as a pickup device.

10 For greater comfort and silence it may, in many cases, be deemed desirable to provide the cane with a resilient head, a head for example, of rubber.

In this event I may provide both the end 15 of the cane body and the end of the finger with mating rubber tips 48 and 49 respectively, as illustrated in Figures 13 and 14, Figure 13 showing these tips in closed position and Figure 14 in open position.

20 The tips 48 and 49 while suitably rubber, may obviously be of any proper cushioning material and are illustrated as fastened to the lower ends of the cane and finger members by screws 50.

25 One of the tips is provided with an artificial nail as indicated at 34².

The nail 34² may or may not be of rubber and one or both of the members may be provided with a magnetic insert as indicated at 30 35².

In view of my invention and disclosure 35 variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

40 Having thus described my invention, what I claim as new and desire to secure by Letters Patent is:—

1. A cane including a handle and a body and having a hollow interior along the 45 handle into the body, a finger normally to lie along a lower portion of the body, a pivot connection between the finger and the body at the upper end of the finger, pinion teeth rigidly connected to the finger and arcuate with respect to the pivot, and mechanism 50 within the hollow including a link, a rack thereon having operative connection with the said teeth, a rocker within the interior of the handle operatively connected with the link and thereby angularly positioning the finger, a pin projecting from the rocker out of the handle interior, means for resiliently opening the finger, and a latch having a release at the handle and in operative position 55 holding the finger closed.

2. A combination cane and pickup device including a cane, a finger normally along the lower part of the cane, a pivoted connection 60 between the finger and cane at the upper end of the finger, means spring pressing the

finger to angularly open about its pivot with respect to the cane, means operative by hand compression at the handle of the cane for closing the finger and means having a release 70 at the handle for normally latching the finger in its closed position against the opening action of the spring.

3. A combination cane and pickup device including a cane, a finger normally along the lower part of the cane, a pivoted connection 75 between the finger and cane at the upper end of the finger, teeth arcuate with respect to the pivot and rigidly connected to the finger, a rack operatively connected to the said teeth, a link having a lower end supporting the rack and mechanism operative at the handle of the cane for vertically shifting the link in order to open and close the finger with respect to the cane.

4. A cane including a handle and a body and having a hollow interior along the handle into the body, a finger normally to lie along a lower portion of the body, a pivot connection between the finger and the body at the upper end of the finger, mechanism 80 within the hollow for angularly positioning the finger with respect to the body and operative at the handle, the lower ends of the cane and finger comprising cooperating pickup members, and an artificial nail 85 mounted upon one and projecting toward the other of the pickup members, the said other pickup member having a recess receiving the projecting nail when the finger is in its closed position.

5. A cane including a handle and a body and having a hollow interior along the handle into the body, a finger normally to lie along a lower portion of the body, a pivot connection between the finger and the body at the upper end of the finger, mechanism 90 within the hollow for angularly positioning the finger with respect to the body and operative at the handle, the lower ends of the cane and finger comprising cooperating pickup members, and an artificial nail 95 mounted upon one and projecting toward the other of the pickup members, the said other pickup member having a recess receiving the projecting nail when the finger is in its closed position.

6. A cane including a handle and a body and having a hollow interior along the handle into the body, a finger normally to lie along a lower portion of the body, a pivot connection between the finger and the body at the upper end of the finger, and mechanism 100 within the hollow for angularly positioning the finger with respect to the body and operative at the handle, normally adjacent rubber tips on the lower ends of the cane and finger, and an artificial nail mounted upon one and normally projecting into the other of the tips.

7. A cane including a handle and a body and having a hollow interior along the handle into the body, a finger normally to lie along a lower portion of the body, a pivot connection between the finger and the body at the upper end of the finger, and mechanism 105 within the hollow for angularly positioning the finger with respect to the body and operative at the handle, the said mechanism including teeth upon the upper end of the finger arcuate with respect to the pivot, a pinion having pivotal support on the body and meshing with the teeth, a rack meshing with the pinion, a link carrying the rack and a lever within the interior of the handle operating the link.

8. A cane including a handle and a body and having a hollow interior along the han- 110 115 120 125 130

dle into the body, a finger normally to lie along a lower portion of the body, a pivot connection between the finger and the body at the upper end of the finger, and mechanism within the hollow for angularly positioning the finger with respect to the body and operative at the handle, the said mechanism including a first class lever in the handle pivoted near the body of the cane, a link pivotally connected to the body end of the lever, a rack upon the lower end of the link, a pinion pivotally mounted on the body and meshing with the rack, a second pinion meshing with the first pinion and the finger carried by the second pinion, the lower ends of the body and finger comprising cooperating pickup members and a pickup device at the lower end of one of the members.

8. A cane including a handle and a body and having a hollow interior along the handle into the body, a finger normally to lie along a lower portion of the body, a pivot connection between the finger and the body at the upper end of the finger, and mechanism within the hollow for angularly positioning the finger with respect to the body and operative at the handle, the said mechanism including a first class lever in the handle pivoted near the body of the cane, a link pivotally connected to the body end of the lever, a rack upon the lower end of the link, a pinion pivotally mounted on the body and meshing with the rack, a second pinion meshing with the first pinion and the finger carried by the second pinion, the lower ends of the body and finger comprising cooperating pickup members and a pickup device at the lower end of one of the members and in which spring means presses the lever toward its position for an open finger and a latch connection between the lever and the interior of the handle normally holds the lever in its position for a closed finger.
